UNITED STATES PATENT OFFICE

2,531,442

CROSS-CHEST BUCKLE FOR PARACHUTE HARNESS

Ralph D. Junker, Ansonia, Conn.

Application October 25, 1948, Serial No. 56,324

4 Claims. (Cl. 244—151)

(Granted under the act of March 3, 1883, as amended April 30, 1928; 370 O. G. 757)

1

The present invention relates to a buckle for a parachute harness and more particularly to a cross-chest buckle for a parachute harness especially of the seat-service type.

A conventional parachute harness of the seat-service type must be quickly attachable and quickly adjustable and generally comprises a pair of risers to keep the shoulder straps in position, the risers being connected by a cross-chest buckle. It has been found that the use of known cross-chest buckles with this type of harness has resulted in injury by gouging to the wearer due to the turning of the buckle at an angle to the body of the wearer when the buckle is stressed. Furthermore, it has been difficult to retain the buckles in position without tacking, thus making it virtually impossible to provide for adjustment of the harness at this point.

Accordingly, an object of the present invention is the provision of a cross-chest buckle for a parachute harness which reduces to a minimum pressures on the chest of the wearer with normal wearing and chute opening impact.

Another object is to provide a cross-chest buckle for a parachute harness which remains in position without tacking but is easily adjustable.

A further object is to provide a cross-chest buckle for a parachute harness which affords maximum protection from accidental shoulder strap dislocation.

Other objects and features of the invention will become apparent as the disclosure is made in the following detailed description of a preferred embodiment of the invention as illustrated in the accompanying sheets of drawings in which:

Fig. 1 is a front elevation illustrating the cross-chest buckle and harness in position.

Fig. 2 is a plan view of the cross-chest buckle connection of Fig. 1; and

Fig. 3 is a side elevation of the cross-chest buckle connection.

Referring now to the drawings, wherein like reference characters designate like or corresponding parts throughout the several views, there is shown in Fig. 1 a parachute harness 11 comprising front body straps 12, leg straps 13, and shoulder straps 14, straps 14 being interconnected by the cross-chest buckle 15.

Buckle 15, shown in detail in Figs. 2 and 3, comprises a pair of unitary adapters or risers 16 adapted to be slidably connected to shoulder straps 14 as shown in Fig. 1. Each riser is preferably made of cast steel and consists of a gen-

2

erally rectangular frame 17 having a central longitudinal bar 18 extending thereacross to form a pair of elongated slots 19. If desired, a metal loop 21, preferably of cast steel may be secured to frame 17 to provide means for attachment of parraft equipment.

Secured to one riser 16, as by means of welding, for example, is a snap hook 22, preferably made of cast steel except for the safety lock and cover thereon. Hook 22 is positioned in a plane substantially parallel to that of riser 16 but slightly thereabove. Secured to the other riser 16 is a ring 23, preferably of cast steel, positioned in a plane substantially perpendicular to that of its riser, substantially all of ring 23 being positioned above the plane of the riser 16 as shown in Fig. 3.

From this construction it can readily be seen that the buckle will be flat against the chest of the wearer with the risers being adjacent the body, thereby acting as a cushion to take the bulk of the pressure exerted. This arrangement therefore reduces to a minimum the pressure on the chest of the wearer resulting from both normal wearing and from impact due to chute opening. Furthermore, since the risers and buckle lie substantially flat against the chest of the wearer and do not turn at an angle to the body when stressed, substantially all possibility of injury due to gouging has been eliminated.

Various modifications and uses are contemplated and may obviously be resorted to by those skilled in the art without departing from the spirit and scope of the invention, as hereinafter defined by the appended claims, as only a preferred embodiment thereof has been disclosed.

The invention described herein may be manufactured and used by or for the Government of the United States of America for governmental purposes without the payment of royalties thereon or therefor.

What is claimed is:

1. In combination with a parachute harness having a pair of shoulder straps, a cross-chest buckle comprising a riser slidably mounted on each of said straps, a snap hook secured to one of the risers and positioned in a plane substantially parallel to that of said one riser, and a ring for detachable engagement with said hook secured to the other of the risers, said ring being positioned in a plane substantially perpendicular to that of said other riser.

2. The combination according to claim 1, wherein said hook and said ring are positioned above the planes of said risers.

3. A cross-chest buckle for a parachute harness comprising a pair of substantially aligned risers, a hook integral with one of said risers and positioned in a plane substantially parallel to and above that of said one riser, and a ring integral with the other of said risers and positioned in a plane substantially perpendicular to that of said other riser, said hook being adapted to detachably engage said ring, and the lowest extremity of said ring being positioned above the lower end of said other riser.

4. A detachable buckle comprising a pair of risers, a snap hook integral with one of said risers and positioned in a plane substantially parallel to that of said one riser, and a ring integral with the other of said risers and positioned in a plane substantially perpendicular to that of said other

riser, said hook detachably engaging said ring and said hook and said ring being positioned above the planes of said risers, respectively.

RALPH D. JUNKER.
